UNITED STATES PATENT OFFICE

EARL R. SWANSON, OF CHICAGO, ILLINOIS, ASSIGNOR TO CHICAGO-CLEVELAND CAR ROOFING COMPANY, OF CHICAGO, ILLINOIS, A CORPORATION OF DELAWARE

RAILWAY CAR

Application filed May 27, 1929. Serial No. 366,404.

My invention relates to railway cars and more particularly to a load lifting device adapted to be associated with the roof structure. A principal object of the invention is to provide means extending longitudinally of the car and supported by the roof affording means for receiving a rope, chain or other hoist device whereby automobiles and similar articles may be raised above the car floor.

A primary feature of the invention consists in providing a car roof, of the type involving carlines and roof sheets, with a beam member extending longitudinally of the car in spaced relation to the roof sheets and with brackets overlapping the top of the carlines for supportingly engaging the undersides of adjacent portions of neighboring roof sheets. A further feature of the invention resides in constructing a car roof, of the type involving carlines and roof sheets with a beam member extending longitudinally of car, said carlines being offset downwardly adjacent their central portions and being rigidly secured to said beam to support the latter in spaced relation to the roof sheets.

Other and more specific features of the invention residing in advantageous forms and combinations and relations of parts will hereinafter appear and be pointed out in the claims.

In the drawings illustrating a preferred embodiment of the invention.

Figure 1 is a fragmentary longitudinal sectional view of the car roof embodying the invention.

Figure 2 is a fragmentary transverse sectional view of the roof construction illustrated in Figure 1.

Figure 3 is an enlarged detailed view of the portion of the roof construction adjacent one of the carlines illustrated in Figure 1.

Figure 4 is a fragmentary enlarged detailed view taken at right angles to Figure

3, the roof sheets and associated seam cap being omitted.

As the construction of the roof on opposite sides of its longitudinal center is identical the transverse sectional view illustrated in Figure 2 depicts only a little more than one-half of the roof structure.

Referring more particularly to the drawings 1 indicates one of the side plate members of the roof structure which is preferably of Z-shape having substantially vertical flanges 2 and 3 connected by a horizontal web portion 4. The end plates 5 of the roof which are, as is well known, rigidly connected to the side plates are also of Z-shape having oppositely projecting vertical flanges 6 and 7 and an intermediate web 8.

Extending continuously from one side of the car to the other are a plurality of carlines 9 which, at their opposite ends, are rigidly connected by brackets 10 to the adjoining side plates 1. Each of the carlines is preferably of inverted channel shape having a web 11 and downwardly projecting substantially vertical sides 12 which terminate in lateral base flanges 13. The roof sheets 14 also extend continuously from one side of the car to the other and respectively span the spaces between the carlines. The lateral edges of each of the roof sheets, with the exception of the outer edge of the end sheets, terminate in upwardly projecting flanges 15 spaced slightly from adjacent sides of the carlines. The outer edges of the end roof sheets are flanged downwardly as at 16 for attachment to the end plates. The eaves edges of the roof sheets are flanged inwardly as at 17 to cooperate with flashing strips 18 secured to side fascias 19 carried by the respective side plates.

The adjoining edges of the roof sheets are connected by seam caps 20 which respectively embrace the carlines. The sides of each of the seam caps are offset to form housings 21 for the upturned flanges of the roof sheets.

The ends of the seam caps may advantageously be flanged downwardly as at 22 and are secured to the side plate by bolts 23. Intermediate their ends the seam caps are firmly secured to their associated carlines by any suitable means. (not shown).

The load lifting device 24, illustrated in the present embodiment as an I-beam, extends longitudinally of the car substantially midway between the ends of the carlines in spaced relation to the roof sheets. The ends of the beam member are preferably rigidly connected to the top flange 6 of the end plates 5 by brackets 25. To support the beam member intermediate its ends each of the channel shape carlines is offset or bent downwardly adjacent their central portions, the amount of offset being solely determined by the clearance desired between the beam member and roof sheets. The beam member is directly secured to the carlines by rivets 26 which respectively pass through the lateral flanges 13 of the carlines and the top flange 27 of the beam member.

By securing the beam member directly to the offset portions of the carlines it will be perceived that the beam member is rigidly supported in spaced relation to the roof sheets so that sufficient clearance is provided between it and the sheets to permit any hoisting device such as a rope, or chain to pass therebetween and be supported by the beam. It is, of course, to be understood, as clearly shown in Figure 2, that the seam caps are not bent downwardly, adjacent their central portions in a manner similar to that of the carlines but extend uninterruptedly from one side of the roof to the other.

To support the roof sheets adjacent the central portion or ridge of the roof means is preferably interposed between them and the carlines. In the present embodiment of the invention this means comprises a substantially flat bar or strip of metal 28 which projects beyond opposite sides of the carlines a sufficient distance to adequately support the roof sheets. Each of the roof sheet supporting members is offset as at 29 to embracingly engage the upper portion of its associated carline immediately above the point of attachment of the beam member, being rigidly connected to the web of the carline by a rivet 30. Adjacent their offset portions the brackets may be conveniently reinforced by corrugations 31.

The usual purlins 32, which are secured to the carlines by bolts 33, are employed for supporting the portions of the roof sheets intermediate the ridge and respective eaves of the roof.

From the foregoing it will readily be appreciated that in addition to providing the roof structure with a rigid hoisting device simple and reliable means is also provided

for supporting the sheets of the roof adjacent the ridge thereof.

I claim:

1. In a roof for railway cars, the combination with a plurality of carlines, of roof sheets respectively associated with and spanning the spaces between the carlines, a beam member secured to said carlines in spaced relation to the roof sheets, and means overlapping the tops of said carlines for supportingly engaging the undersides of adjacent portions of neighboring roof sheets. 70

2. In a roof for railway cars, the combination with a plurality of carlines, of roof sheets respectively associated with and spanning the spaces between the carlines, a beam member secured directly to said carlines, said beam extending longitudinally of the car in spaced relation to the roof sheets, and brackets secured to and overlapping the tops of said carlines for supportingly engaging the undersides of adjacent portions of neighboring roof sheets. 75

3. In a roof for railway cars, the combination with a plurality of carlines, of roof sheets respectively associated with and spanning the spaces between the carlines, a beam member extending longitudinally of the car in spaced relation to the roof sheets, said carlines being offset downwardly adjacent their central portions for attachment to said beam in overlapping engagement therewith. 80

4. In a roof for railway cars, the combination with a plurality of substantially channel shaped carlines having base flanges, of roof sheets respectively associated with and spanning the spaces between the carlines, a beam member extending longitudinally of the car in spaced relation to the roof sheets, each of said carlines being bent downwardly adjacent its central portion and the flanges of each being secured to said beam member. 85

5. In a roof for railway cars, the combination with a plurality of carlines, roof sheets respectively associated with and spanning the spaces between the carlines, a beam member extending longitudinally of the car in spaced relation to the roof sheets, said carlines being offset downwardly adjacent their central portions whereby they may be overlappingly secured to the said beam in spaced relation to the roof sheets, and means secured to the top of each of said carlines adjacent the offset portion thereof for supportingly cooperating with adjacent portions of adjoining roof sheets. 90

6. In a roof for railway cars, the combination with a plurality of carlines respectively having a web and downwardly extending sides terminating in lateral base flanges, of roof sheets respectively associated with and spanning the spaces between the carlines, a beam member extending longitudinally of the car in spaced relation to the roof sheets, each of said carlines being bent downwardly 125

adjacent its central portion and the flanges of each being secured to said beam member, and brackets respectively secured to the webs of said carlines adjacent the point of attachment of the beam member to the carlines for supportingly engaging the undersides of adjacent portions of adjoining roof sheets.

7. In a roof for railway cars, the combination with a plurality of carlines, of roof sheets respectively associated with and spanning the spaces between the carlines, a beam member secured to said carlines in spaced relation to the roof sheets, and a bracket arranged in embracing overlapping relation with each carline and having laterally projecting portions underlying adjacent portions of neighboring roof sheets for supporting the latter.

20 In testimony whereof I affix my signature.
EARL R. SWANSON.
